BY *Munn & Co.*
ATTORNEYS

UNITED STATES PATENT OFFICE.

THOMAS L. LILLY, OF MINONK, ILLINOIS.

END GATE.

Application filed June 4, 1921. Serial No. 474,922.

To all whom it may concern:

Be it known that I, THOMAS L. LILLY, a citizen of the United States, and resident of Minonk, in the county of Woodford and 5 State of Illinois, have invented certain new and useful Improvements in End Gates, of which the following is a specification.

This invention relates to carriages and wagons and more particularly to end gates, 10 and improved fastening means therefor associated with the wagon body.

The invention embodies a combination flat and swinging eye-bolt end gate fastener for wagons and auto trucks for fastening the 15 end gate embodying a plurality of sections to the wagon body or auto truck body, thus obviating the necessity of employing wagon rods or chains connecting the opposed sides of the wagon box or truck body and which 20 cannot be drawn out in close quarters while with the present fastener the end gate may be opened in a very minimum space.

Other and further objects of my invention will become readily apparent to persons 25 skilled in the art, from a consideration of the following description when taken in conjunction with the accompanying drawings, wherein:

Figure 1 is a fragmentary perspective 30 view of the wagon box or truck body having an end gate and fastening means constructed in accordance with the invention.

Figure 2 is an enlarged vertical sectional 35 view of one of the side boards of the box or body and showing the fastening means associated therewith, and

Figure 3 is a perspective view of one of the slotted keepers employed with the fastening means.

Referring to the drawings in detail, in 40 which like reference characters designate corresponding parts throughout the several views and wherein is illustrated the preferred embodiment of the invention, a 45 wagon body or auto truck box is shown having the bottom portion or bed 10 and the side boards 11 constituting the permanent sections of said side boards or sides of the body. Above the sides 11 are disposed 50 boards or sections 12, which may be supplemented by boards or sections 13, thereby serving as an effective means for increasing the capacity of the body or box. In order 55 to retain the boards or sections 12 and 13 in position, cleats 14 in the form of strips or metal or the like are secured against the

sections 12 at the outside, as indicated at 15 and the lower portions thereof extend below the bottom edges of the boards or sections 12 to engage the outer faces of the side 60 boards 11 constituting the permanent sections thereof. In this way, the sections or boards 12 will accommodate themselves to the boards 11 and in a like manner, cleats or strips 16 are secured as indicated at 17 65 to the outer faces of the boards or sections 13 so that the lower portions thereof projecting beneath the lower edges of the boards or sections 13 engage the outer faces of the sections 12 and for abutting the forward 70 edges of the secured upper ends of the cleats or strips 14, as particularly indicated in Figure 1 of the drawing, will prevent rearward displacement of the upper sections 13, as it is thought will be clearly apparent, 75 from an inspection of the drawings.

The end gate proper includes a stationary section 18 which is arranged across the top portion of the permanent or normal body portion formed by the sides 11, thus extending 80 across the minor portion of the sides 11 at the top thereof and having hinged thereto, as indicated at 19 so as to swing outwardly and rearwardly from its lower edge a section 20 which latter section extends 85 over the entire lower portion of the opening in between the sides 11. In order to secure the stationary section 18 in position, a transverse bar 21 is secured against the rear face thereof, as shown at 22, and has the ends thereof formed with cleats 23 produced by forming or bifurcating the ends of the bar or strip 21 of metal in the manner of forks, the furcations 24 being directed 90 rearwardly at right angles to the bar proper so that the bifurcations or slots thus formed are rendered similarly continuous to the ends of the cleats or bars. It will be observed that the slots or recesses are produced at the projecting ends of the bar or cleat 95 and in order to secure the same in position, eye-bolts 25 are secured through the side boards 11 intermediately of the top and bottom edges of the tail gate section 18, the shank extending through an opening in each side, as indicated at 26 and retained in position by lock nuts or the like 27, while the eyes 28 are horizontally disposed in an outward direction. Engaged with the eyes 28 are the eyes 29 of eye-bolts 30 having washers 31 mounted on the shank portions thereof, 100 as well as nuts 32 preferably in the form

of wing or thumb nuts. By this means, the shanks of the eye-bolts 30 may be swung into the slots of the bar or strips 21, or the cleats produced thereby and over the stops 5 or shoulders produced by the rearwardly extending portions or retaining members 24, after which the nuts 32 may be screwed home to secure the section 18 in position. Also, it will be understood that said section 10 may be readily detached by unscrewing the nut 32 and displacing the same from the cleat through the slots 23.

In order to facilitate handling of the swinging or dumping section 20 which moves 15 outwardly and rearwardly, a handle 33 is provided and the section 20 which is hinged on a horizontal axis to swing outwardly and rearwardly or upwardly, if desired, is adapted to be secured in a closed position by 20 the same means as heretofore described in connection with the upper stationary removable section 18. However, inasmuch as the construction and operation of the fastening means is the same, the description of one, 25 it is thought, will be sufficient and the parts may be understood by reference to the drawing with corresponding reference characters.

It will be noted that the sections 18 and 20 of the tail gate cover the vertical rear 30 edges of the side boards 11 and in order to cover the rear edges of the sections 12 and 13 of the sides or side boards of the body or box, boards or sections 34 and 35 are provided for the tail gate, each having a short 35 trip or cleat 36 secured near its upper and lower edges on each side, or a pair at each side or end of said sections 34 and 35 formed with slots and retaining means corresponding to the strips or bars 21 employed in connection with the sections 18 and 20 and engaged by corresponding pairs of clamping means or eye-bolts and nuts as employed in connection with the cleats at the ends of the bars or strips 21. However, the sections 34 40 and 35 are separable and detachable and have no connection with one another, while the sections 18 and 20 are connected, by reason of the section 20 being hinged or pivoted to the section 18 to swing to an open 45 position or to be closed and held in a closed position by the fastening means above referred to.

It will thus be seen that the sections 34 and 35 may be employed or removed as desired, the corresponding side board sections 50 12 and 13 being used or removed therewith, depending upon the capacity of the wagon body or box desired, although it is apparent that the construction may be employed in connection with automobile truck bodies as well as wagon bodies or boxes.

On an automobile truck having a hoist 55 for the body, the hinge section 20 when released by the end fastening means, may open automatically as the body is raised, and said

hinged or dumping section may swing upwardly when employed in connection with a wagon box having no provision for hoisting or raising the same in the manner of an automobile truck body or box. This will facilitate dumping at a grain elevator, the dumping action being accomplished by releasing the bolt or fastening means at the ends of the bar or section 21 at the bottom only and the cleats produced by the projecting ends thereof at the lower edge of the swinging section 20 of the tail gate. When the fastening means is released, the swinging gate section will automatically open upon the raising of the front of the body, the removable stationary section 18 serving as a mounting therefor. It is therefore unnecessary to detach the gate in order to dump the load, while if necessary, the sections of the end gate may be readily removed in an instant, for loading or unloading heavy articles or those containing considerable bulk and which cannot be discharged by dumping or which cannot be loaded by a shovel or in other suitable ways, thus the loading and unloading operation can be accomplished in a short time by the removal of the tail gate sections from the sides of the wagon box or body. In hauling corn, wheat or other grain or similar material, both of the sections 12 and 13 are used, or the section 13 together with the corresponding tail or end gate section 35 may be entirely removed, but employed in hauling oats which are much lighter or similar material requiring a larger capacity. Also it will be apparent that the middle section may be removed and the upper section employed with the bottom section in order to reduce the capacity as compared when employing the middle section in connection with the bottom section by reason of the fact that the top section is narrower than the middle section, or vice versa.

It will also be apparent that the end or tail gate sections may be firmly held in position by the fastening devices when the eye-bolts 30 are swung at right angles to the eye-bolts 25 through the medium of the pivotal connection of said parts and that the eye-bolts 30 will drop loosely at the sides 110 when the end gate sections are removed, or when the section 20 is released to permit the automatic opening thereof when the contents 115 is being discharged. Obviously, it will be manifest that when the nuts are loosened on the threaded shanks of the bolts 30 they may be passed over the rearwardly directed end 24 of the projecting ends of the plates or bars 36 and 21 respectively and when turned 120 down to clamp the washer 31 against the rear faces thereof, the fastening means will be securely held from outward displacement by the shoulders or stops produced by the right angularly bent end portions, the nuts 125 and washers in this position straddling the 130

slots or recesses 23 in the manner clearly shown in Figure 1 of the drawings. Furthermore, any wear on the gate may be accommodated or compensated for through the 5 medium of the take-up washers 31 and the thumb nuts 32, thus insuring a tight fit between the end gate sections and the side boards.

In view of the foregoing, it is thought 10 that the operation of the device will be readily apparent and in view of the simplicity and practical value that it will readily commend itself to those skilled in the art.

I claim:

15 In a structure of the character described, a pair of edgewise disposed spaced supporting members, an end gate section swingingly supported in spanning relation to the adjacent ends of the supporting members, a 20 bar secured to the end gate section to extend longitudinally of the latter and to project at

its one end beyond the corresponding end of the end gate section, said bar having its projecting portion bifurcated longitudinally from the end thereof to the adjacent end of 25 the end gate section, the bifurcated portion being bent laterally away from the adjacent supporting member and a latching member swingingly supported upon said adjacent supporting member and having a portion 30 adapted to be swung between the furcations of the said projecting portion of the bar, and means adjustable on the latching member for movement into and out of engagement with the said bar at the inner side of the laterally bent end portion, to prevent or permit 35 the latching member to disengage the bar, said last means including a nut threadedly engaging the latching member and a spacing washer disposed on the latching 40 member between said nut and the bar.

THOMAS L. LILLY.
